JOHN HARVEY GOLDEN, OF BUFFALO, NEW YORK.

CARBURETER.

1,253,484.

Specification of Letters Patent. Patented Jan. 15, 1918.

Application filed August 7, 1916. Serial No. 113,497.

To all whom it may concern:

Be it known that I, JOHN HARVEY GOLDEN, a citizen of the United States, residing at Buffalo, in the county of Erie and State of New York, have invented new and useful Improvements in Carbureters, of which the following is a specification.

This invention relates to a carbureter designed more especially for producing an explosive gas from kerosene and other heavy or low grade hydrocarbons for use in internal combustion engines, such as the motors of automobiles.

Its chief object is the provision of a carbureter which produces a practically smokeless and odorless gas from such heavy hydrocarbons, rendering the cost of running a car or engine much less than by the use of gasolene; which insures a constant feed of fuel to the carbureter, and which enables a cold motor to be readily started without the aid of gasolene or other additional explosive gases or mixtures.

Further objects are to so construct the carbureter as to insure an ample supply of air in running at intermediate and high speeds as well as at low speed, and to improve the device in other respects.

In the accompanying drawings:

Figure 1 is a sectional elevation of a carbureter embodying the invention. Fig. 2 is a horizontal section thereof on line 2—2, Fig. 1. Fig. 3 is a fragmentary vertical section on line 3—3, Fig. 2. Fig. 4 is a horizontal section on line 4—4, Fig. 1.

Similar characters of reference indicate corresponding parts in the several figures.

1 indicates the bowl or fuel chamber of the carbureter adapted to contain a suitable quantity of kerosene or other appropriate liquid hydrocarbon. Fuel is delivered into said chamber from a supply chamber 2 communicating therewith by a passage 3 and having an inlet 4 controlled by a needle or float valve 5, for automatically regulating the liquid level in the fuel chamber 1 in the customary manner. A fuel supply pipe 6 communicates with the inlet 4. In the example shown in the drawings, the needle valve is carried by one arm of a lever 7 whose other arm is attached to the float 8 arranged in the fuel chamber. This float may be of the usual horseshoe form and partly surrounds a mixing tube or chamber 9 to which leads a main or primary air supply passage or conduit 10 and an auxiliary

air supply passage 11. Leading from said mixing tube is a mixture outlet or neck 12 which is connected with the motor by the customary manifold, not shown. A port 13 controlled by an automatic valve 14 connects the auxiliary air passage 11 with the primary air passage 10, the weight or resistance of this valve being such that it remains closed in running at starting or low speeds and opens under the increased suction produced by the motor at intermediate and high speeds, in a manner common to this class of carbureters. In the construction shown, this valve is arranged to slide vertically on a guide rod 14^a and is properly weighted to close by gravity, but if desired, it may be provided with a spring for this purpose.

It is important that the auxiliary valve should open promptly and supply the necessary additional volume of air in running at high and intermediate speeds. To effect this result, suitable means are provided for directing a portion of the incoming air upwardly toward and against the face of said valve. The preferred device consists of a deflector or curved lip 15 arranged to extend from the upper front end of the primary air passage 10 to the rear portion 16 of the seat of said valve, the lower portion of the deflector extending forwardly beyond the rear side of the valve, as shown in Fig. 1.

The primary air passage 10 communicates with the mixing tube 9 by an ascending passage 17 in which is arranged the mouth of an atomizer or fuel-nozzle 18 which delivers a spray of kerosene into said tube where it is mixed with the air entering through the primary or the auxiliary air passage, or both. The lower end of said nozzle opens into the fuel chamber 1 and the supply to the nozzle is regulated by the customary needle valve 19. In the preferred construction shown in the drawings, the lower rear wall 20 of the auxiliary air passage 11 is curved upwardly and extended to or nearly to the mouth of the atomizing nozzle, as shown in Fig. 1. By this construction the auxiliary air current is deflected upwardly and toward the front side of the mixing tube 9, preventing it from interfering with or choking back the primary air current ascending through the passage 10, when the auxiliary valve 14 is open.

As shown in the drawings, the body of the carbureter preferably consists of front and rear sections, each cast in one piece. These

sections meet in a substantially vertical joint 21 intersecting the auxiliary air passage 11 between the automatic valve 14 and the mixing tube 9, and a substantially horizontal joint 22 located at the junction of the primary air passage 10 and the ascending passage 17. These parts are secured together at said horizontal joint by a clamping bolt 23 passing through the bottom of the front section and 20 engaging a spider 24 carried by the rear section, and the parts are united at said vertical joint by clamping bolts 25 passing through perforated flanges on the contiguous portions of the front and rear sections.

15 Located within the lower portion of the fuel chamber 1 and submerged in the kerosene is a suitable device for heating the liquid fuel. This device preferably consists of a naked electric resistance coil 26 of German silver or other appropriate material, having its ends connected with a storage battery or other source of energy, not shown. The circuit in which this heating coil is included is controlled by a suitable switch 20 which when the carbureter is applied to an automobile, may be conveniently mounted on the dash of the car. In the construction illustrated in the drawings, the coil is insulated from the body or bowl by lining the latter with mica or other insulating material 27. The ends of the coil are attached to upright posts 28 located in the bowl at opposite sides of the mixing tube 9 and carried at their upper ends by binding posts 29 extending through the wall of the bowl and suitably insulated therefrom.

In addition to the heating coil 26, a similar supplemental heating coil 30 is preferably placed in the mixing tube 9 or the outlet neck 12, or at the junction of these members, as shown, to vaporize any fuel-atoms not sufficiently broken up to form a proper explosive mixture and to maintain the vaporized kerosene in a heated condition, 40 thereby preventing condensation thereof on its way to the motor and preserving its maximum explosive power. This supplemental coil may be connected with the same source of energy as the heating coil and controlled by the same switch. This coil may 45 also be used to advantage in starting the motor without the use of gasoline or other additional explosive gas, as hereinafter more fully described.

55 To obtain the best results and effect prompt starting of the motor, it is desirable to heat the body of kerosene in the carbureter-bowl to a comparatively high temperature, say from 220° to 370° Fahrenheit. Ordinarily, the foam or bubbles resulting from such heating and boiling of the kerosene would rise in the bowl to such a height as to abnormally raise the float and cause the needle valve 5 to cut off the further supply 60 of fuel to the float chamber, thus impairing

the operation of the motor and stopping it in a comparatively short time.

To overcome this objection, I submerge in the body of the kerosene one or more blocks or pieces 31 of a material which has the 70 property of checking or subduing such bubbling of the kerosene sufficiently to avoid interference with the normal action of the float and insure a constant and uniform fuel-feed to the carbureter and a regular and 75 steady action of the motor. A porous, stone-like material which becomes heated more slowly than the kerosene is suitable for this purpose. Pumice has proved very satisfactory, but any other equivalent substance, 80 such as fire-clay, may be employed. Owing to this differential heating of the kerosene and the pumice blocks, the bubbles produced by boiling flow from the heating coil toward the submerged blocks and remain 85 principally under the surface of the liquid. Foaming or bubbling at its surface is thus checked and kept down, so as not to interfere with the proper and normal action of the float, as above described. In the construction shown in the drawings, two of such pumice blocks are mounted on the posts 28 respectively, but they may be otherwise supported or held in place in the fuel-bowl.

In the use of the carbureter, the kerosene in the bowl 1 is highly heated by cutting in the main heating coil 26 alone, with a current of about 25 amperes. To start the motor, said main coil is cut out and the supplemental coil 30 cut in. This results in the production of a powerful explosive gas which permits the motor to be promptly started without the preliminary use of gasoline, thus simplifying the construction of 100 the carbureter as well as effecting a material saving in fuel.

After the motor has been started, the supplemental coil may be cut out and the main coil again cut in at a low amperage, say 110 about two amperes. This reduced heating action of the main coil is sufficient, inasmuch as the carbureter after the motor has been started, is highly heated by the incoming hot air which in turn is heated by the customary stove applied to the exhaust manifold of the motor, the carbureter being also heated by the incoming kerosene which is heated by passing through the usual worm or coil applied to said manifold.

115 Summarizing the advantages of this carbureter, it permits the use of kerosene instead of the more expensive gasoline; the exhaust gases are smokeless and have no offensive odor; a cold motor can be started in a relatively short time without the aid or preliminary use of gasoline or other explosive gas; very little carbon is deposited 120 in the cylinders, requiring them to be cleaned less frequently, and the explosive 125

mixture is more powerful than that produced by gasoline, obtaining correspondingly greater mileage.

I claim as my invention:

5. In a carbureter, a float chamber adapted to contain liquid hydrocarbon fuel, means for heating the contents of said chamber, and a substance in said chamber having the property of subduing the bubbles produced by the boiling of said liquid. 35
10. 2. In a carbureter, a float chamber adapted to contain liquid hydrocarbon fuel, means for heating the contents of said chamber, and a substance in said chamber having the property of becoming heated less rapidly than the liquid fuel in which it is submerged. 40
15. 3. In a carbureter, a float chamber adapted to contain liquid hydrocarbon fuel, means for heating the contents of said chamber, and a porous body in said chamber having the property of becoming heated less rapidly than the liquid fuel in which it is immersed and operating to subdue the bubbles 45
20. produced by the boiling of said liquid. 50
25. 4. In a carbureter, a float chamber adapted to contain liquid hydrocarbon fuel, means for heating the contents of said chamber, and a block of pumice stone arranged in said chamber and adapted to be immersed 55
30. in its contents.

5. In a carbureter, a chamber for liquid hydrocarbon fuel, means for heating the contents of said chamber, a valve for regulating the feed of the fuel to said chamber, a float in said chamber controlling said valve, and means in said chamber for subduing the bubbles created by the boiling of said liquid fuel.

6. A carbureter, comprising a float chamber adapted to contain liquid hydrocarbon fuel, an electric coil arranged within said chamber for heating its contents, and a substance in said chamber having the property of subduing the bubbles produced by the boiling of said fuel.

7. A carbureter, comprising a float chamber adapted to contain liquid hydrocarbon fuel, posts arranged in said chamber and forming electric terminals, an electric heating coil arranged in said chamber and connected with said posts, and porous blocks mounted on said posts and having the property of subduing the bubbles produced by the heating of said fuel.

8. A carbureter, comprising a float chamber adapted to contain hydrocarbon fuel, an electric coil arranged in said chamber for heating its contents, and a block of pumice-stone arranged in said chamber and adapted to be immersed in its contents.

JOHN HARVEY GOLDEN.
